Specification of Letters Patent.

Patented Oct. 1, 1912.

Original application filed November 8, 1907, Serial No. 401,264. Divided and this application filed March 24, 1911. Serial No. 816,699.

To all whom it may concern:

Be it known that we, JOHN W. HAMMOND and JOSEPH F. DONAHUE, both citizens of the United States, and residents of Taunton, county of Bristol, and Boston, county of Suffolk, respectively, State of Massachusetts, (whose post-office addresses are Taunton, Massachusetts, and care of Mead Morrison Mfg. Co., Cambridge A, Boston, Massachusetts, respectively,) have invented an Improvement in Hoisting Apparatus, of which the following description, in connection with the accompanying drawings, is a specification, like letters on the drawings representing like parts.

The present invention relates to a hoisting apparatus and is embodied in an apparatus of the kind commonly used in hoisting or transferring coal, in which the position of a bucket is controlled by a trolley longitudinally movable upon a boom, combined with separate means for raising and lowering the bucket and opening and closing the same. In hoisting apparatus of this class, two separate engines are commonly employed, one to control the operation of lowering and hoisting the bucket and opening and closing the same, and the other to control the movement of the trolley along the boom to position the bucket, it being common practice to operate the two engines separately, and to employ an attendant to take charge of each engine.

In the operation of the hoisting apparatus, the trolley engine is first operated to haul the trolley and bucket suspended therefrom to the proper position, after which the trolley engine is stopped and the trolley held by setting a suitable brake. The hoisting drum is then set free to lower the bucket which is opened and closed by suitable manipulations of the apparatus operated by the main hoisting engine, after which the said hoisting engine is put in operation to raise the bucket, the trolley brake then being released to permit the trolley to run back and bring the bucket into proper position for dumping the load. This operation of the trolley engine is commonly performed by releasing the brake and also a clutch which frees the trolley cable-drum from the engine, permitting the trolley to run back through the action of gravity.

It is the purpose of the present invention to arrange the trolley engine and its operating devices so that they may be under the control of the operator of the hoisting engine, and also to simplify the control so that the hoisting engine operator will not have any material amount of extra work. To this end, the clutch commonly employed in connection with the trolley engine is dispensed with and the engine itself is allowed to reverse in the return movement of the trolley by employing a relief valve which allows the steam trapped in the engine cylinders to escape or exhaust, so that the engine will reverse freely when the relief valve is open. The trolley engine is also provided with an automatic brake which may be operated by steam pressure, so that the brake and relief valve may be operated by a common actuating device. The trolley engine throttle may be controlled by a foot treadle which is also arranged to operate on the relief valve to close the same when the engine is to be operated, so that the hoisting engine operator, in order to control the trolley engine likewise, has only one additional foot lever to take care of and one actuating device which can be connected with and operated in common with one of the levers employed in the control of the hoisting engine. The control of the entire hoisting operation, by these expedients, is accomplished by means of two treadles which are also operated separately, two handle levers which are the same as those now employed in the control of the hoisting engine alone, and a single manual actuating device which may conveniently be arranged in the shape of a grip handle connected with one of said levers.

Figure 1 is a perspective view showing in diagram an apparatus embodying the invention: Fig. 2 is a vertical sectional detail for the purpose of illustrating more clearly the specific construction and arrangement of the controlling devices: Fig. 3 is a general side elevation of the complete apparatus, with parts shown in section; and Fig. 4 is a detail showing the hoisting drum.

The main hoisting apparatus consists of drums A and A² which are loosely mounted on a shaft provided with a gear A³ through which it is driven from the main hoisting

engine A⁴. These drums are provided, respectively, with clutch surfaces A¹⁰ and A²⁰, so that they can be caused to rotate with the shaft, or release therefrom, the clutches being operated through levers C and D which are under the control of the operator; each of the drums is provided with a rope leading to a grab bucket A⁵, one of the ropes A⁶ constituting the main hoisting rod, while the other, A⁷, controls the opening and closing of the bucket A⁵. These ropes pass over a trolley G mounted on a trolley boom G², so that the lowering and hoisting of the bucket, and the opening and closing thereof are controlled through the action of the levers C and D, while the hoisting engine A⁴ is started and stopped by means of a throttle A⁸ connected by a rope A⁹ with a treadle B. In the construction shown, the levers C and D are connected through links C² and D² with rocker members C³ and D³ which, in turn, are connected with the clutch-operating mechanism.

The trolley G which positions the bucket prior to the hoisting operation, and then transfers the bucket to the dumping point is mounted on the trolley boom G² and is under the control of the trolley engine E, the present invention relating mainly to the devices by which the said trolley engine is caused to perform its functions at the proper time. Starting with the bucket empty, the first step in the operation consists in operating the trolley engine to haul the trolley to the position from which the bucket is to be lowered. This is accomplished by starting the trolley engine so as to produce a rotation of the winding drum E² and wind in the trolley cable E³. The starting of the trolley engine is produced by pressing a treadle a shown as connected by means of a cable a² running over sheaves a³ with a weighted lever b² connected with a throttle valve b which controls the admission of steam to the engine E.

When the trolley has been hauled out of the proper position the engine E is stopped by releasing the treadle a, the throttle valve lever b² being provided with a weight b³ whereby the throttle is closed automatically when the treadle is released. This stops the operation of the engine E and in order to hold the trolley, the drum E² is provided with a brake which is herein shown as a band brake E⁴ arranged to be operated automatically by means under the control of the hoisting engine operator. This brake is normally set, but is arranged to be released during the operation of the engine E by means of an actuating device which is herein shown as a grip lever c connected with the lever C which controls the initial operation of the hoisting engine. The brake E⁴ may conveniently be operated by steam pressure, the brake band being herein shown as connected

by means of a cable e running over a sheave e², with the rod e³ of a piston e⁴, operating in a cylinder e⁵. Steam is admitted to said cylinder through the pipe f under the control of a valve which consists of a slide member g longitudinally movable in a steam chest g² having a steam-inlet duct g³ and exhaust duct g⁴. The slide valve g is shown as in the form of a longitudinally movable plunger having a rod g⁵ projecting through a stuffing box in the end of the steam chest and acted upon by a spring g⁶ which tends to hold it in the position shown in Fig. 2. In this position live steam is admitted to the brake cylinder e⁵ from the duct g³ through the pocket g⁷ formed in the valve member g. The actuating device c is arranged to shift the valve g through the action of the link e² and elbow lever c³, thereby producing a movement of the valve member g to the left, Fig. 2. Such movement closes the steam duct g³ and connects the duct f with the exhaust duct g⁴, thus permitting the steam to exhaust from the brake cylinder e⁵ and release the brake.

In the operation of the apparatus as thus far described, the attendant releases the brake on the trolley engine by gripping the actuating member c, at the same time starting the engine by depressing the treadle a, thus causing the trolley to be pulled out to the proper position, at the end of which time the engine is stopped by releasing the treadle a, and the brake is set by releasing the grip c. The grip c is preferably connected, as described, with one of the levers which control the clutches of the hoisting engine. In the construction shown, the said grip is connected with the lever C which operates the clutch controlling the lowering and hoisting of the bucket. The opening and closing of the bucket to fill the same are then controlled by means of the lever D, after which the bucket is hoisted by starting the hoisting engine through the operation of the treadle B and setting the clutches through the operation of the levers C and D. It then becomes necessary to release the brake on the trolley engine drum to permit the trolley to run back which is accomplished by again gripping the handle c. In order to dispense with the clutch connecting the trolley engine with the trolley engine drum it is necessary to provide means whereby the engine may be permitted to reverse freely during the movement of the trolley and this is accomplished by providing the intake pipe F which leads to the trolley engine E with a relief valve F² which opens communication between said pipe and an exhaust passage F³. This permits the steam trapped in the cylinders upon the stopping of the engine to escape so that there is no pressure to prevent the action of the pistons in the reverse running of the engine.

Since the engine must run free when the brake is released, the relief valve is arranged to be connected with the brake piston c^4 , the connection being herein shown as a cable a^2 running over sheaves e^7 and connected with a lever F^2 which operates the relief valve F^2 . Upon releasing the grip e , therefore, the spring g^6 acts to open the steam passage into the brake cylinder e^5 , the movement of the brake piston c^4 then setting the brake, and at the same time acting on the lever F^2 to open the relief valve F^2 so that the engine will be free, when the brake is released, to run backward through the action of gravity. In starting the trolley engine E , it is necessary to close the relief valve F^2 , before opening the throttle b , and for this purpose the cable a^2 which is connected with the treadle a is also connected through a spring a^4 with the lever F^2 , the connection between the cable a^2 and the lever b^2 being by means of a slot a^{40} formed in a link a^{41} , and a pin b^{20} on the lever b^2 to allow for the necessary lost motion. In the first movement of the cable a^2 , the slot a^{40} admits of the closure of the relief valve before the lever b^2 is acted upon to open the throttle b and the spring a^4 admits of the necessary further movement to open the throttle after the relief valve has been closed.

From the foregoing description, it will be seen that the trolley engine can be controlled by the attendant who is taking care of the hoisting engine with very little additional trouble, so that the services of one attendant are saved while there is no danger of the confusion which may arise when the work is divided between two attendants stationed in different towers or different parts of the tower, as is now common practice. Furthermore, by locating the brake controller on the main engine lever the operation is convenient for the reason that the operation of the brake and of the main controlling lever are consecutive, so that the said main controlling lever must be in the hands of the attendant during this period in the operation. Furthermore, since the brake is set a greater part of the time, the work is accomplished by arranging the spring so that the brake is automatically held set and manually released.

This application is a division of our pending prior application, Serial No. 33,401,261, filed November 8, 1907.

Claims.

1. In a hoisting apparatus, the combination with a trolley operating engine, of a controlling device for a main hoisting drum, a throttle for the trolley engine, an automatic brake for the trolley engine drum; and a relief valve for the trolley engine arranged to cooperate with said brake, substantially as described.

2. In a hoisting apparatus, the combina-

tion with a trolley of a grab or bucket, a hoisting rope and an opening and closing rope for the bucket, a rope winding drum for each rope, friction devices for each drum, a pair of bucket controlling levers to control each a friction device, a rope winding drum for the trolley, a pressure fluid engine connected to drive the drum, throttle and relief means for the trolley drum engine, a brake for the trolley drum, and means within the control of the bucket controlling operator for controlling said throttle and relief means and said brake.

3. In a hoisting apparatus, the combination with a trolley of a grab or bucket, a hoisting rope and an opening and closing rope for the bucket, a rope winding drum for each rope, friction devices for each drum, a pair of bucket controlling levers to control each a friction device, a rope winding drum for the trolley, a pressure fluid engine connected to drive the same, means for relieving the pressure of said engine, a brake, and means associated with the bucket controlling levers for controlling said brake and pressure relief means.

4. In a hoisting apparatus, the combination with a trolley of a grab or bucket, a hoisting rope and an opening and closing rope for the bucket, a rope winding drum for each rope, friction devices for each drum, a pair of bucket controlling levers to control each a friction device, a rope winding drum for the trolley, a pressure fluid engine connected to drive the same, means for relieving the pressure of said engine, a brake, and an auxiliary hand lever pivotally mounted upon one of the bucket levers for controlling the pressure relief means.

5. In a hoisting apparatus, the combination with a trolley of a grab or bucket, a hoisting rope and an opening and closing rope for the bucket, a rope winding drum for each rope, friction devices for each drum, a pair of bucket controlling levers to control each a friction device, a rope winding drum for the trolley, a pressure fluid engine connected to drive the same, means for relieving the pressure of said engine, a brake, and an auxiliary hand lever pivotally mounted upon one of the bucket levers for controlling the pressure relief means and the brake.

6. A hoisting apparatus having a trolley, a bucket, a pair of hand operated devices for controlling the bucket, a rope winding drum, and a pressure fluid engine connected thereto for actuating the trolley, pressure relief means for the engine and means for controlling said pressure relief means associated with said hand operated device for the bucket and adapted to be actuated by the hand of the operator while still maintaining his hold upon the hand operated devices.

7. A hoisting apparatus having a trolley, a bucket, an operating rope leading to the

bucket, a traversing rope leading to the trolley, a trolley winding drum, a pressure fluid engine connected thereto, pressure relief means for the engine and means permitting the operator to control said bucket operating rope and said pressure relief valve with a single hand.

8. The combination with a grab or bucket of a friction lever, a traversing rope, a rope winding drum, a pressure fluid engine connected to turn the drum, a throttle, a valve, a brake, and means for backing down the engine while connected to the drum.

9. The combination with a bucket of the engine E, drum E² and the relief valve F².

10. The combination with a bucket of a pair of bucket operating levers, a traversing rope, a drum, a pressure fluid engine, relief means, and means at the bucket operator's position for controlling the relief means.

11. The combination with a bucket of a pair of bucket operating levers, a traversing rope, a drum, a pressure fluid engine, relief means and means including a grasping device on one of the bucket operating levers for controlling said relief means.

12. The combination with a bucket of a pair of bucket operating levers, a traversing rope, a drum, a pressure fluid engine, relief means and means including a pivoted hand grip on one of the bucket operating levers for controlling said relief means.

13. The combination with a bucket of a pair of bucket operating levers, a traversing rope, a drum, a pressure fluid engine, engine throttle and relief means and means at the bucket operator's position for controlling the throttle, and relief means including a foot lever and a manually operable control device.

14. The combination with a bucket of a pair of bucket operating levers, a traversing rope, a drum, a pressure fluid engine, throttle and relief means for the engine and means including a foot lever at the bucket operator's position for controlling said throttle and relief means.

15. The combination with a bucket of a pair of bucket operating levers, a traversing rope, a drum, a pressure fluid engine, a brake to control the traversing rope, throttle and relief means for the engine, and means including two movable control elements at the bucket operator's position for controlling said brake, throttle and relief means.

16. The combination with a bucket of a pair of bucket operating levers, a traversing rope, a drum, a pressure fluid engine, a brake to control the traversing rope, throttle and relief means for the engine, and means at the bucket operator's position for controlling said brake, throttle and relief means.

17. The combination with a bucket of a pair of bucket operating levers, a traversing

rope, a drum, a pressure fluid engine, a throttle for the engine, a relief valve and controlling devices at the operator's position for said throttle and relief valve including a hand grip on one lever for controlling the relief and a foot lever for controlling the throttle.

18. The combination with a bucket of a pair of bucket operating levers, a traversing rope, a drum, a pressure fluid engine, a throttle, relief means and controlling devices at the bucket operating levers for controlling said throttle and relief means including a hand control element and a foot lever for the throttle.

19. The combination with a bucket of a pair of bucket operating levers, a traversing rope, a drum, a pressure fluid engine, a brake, a throttle, relief means, and controlling devices at the bucket levers for controlling the brake, throttle and relief means including a hand control element for the brake and the relief means, and a foot lever for the throttle.

20. The combination with a bucket of bucket ropes, winding drums and frictions, a pair of bucket operating levers, a traversing rope, a rope winding drum and a pressure fluid engine to turn the same, a brake for controlling the traversing rope, throttle and relief means and means at the bucket operator's position for controlling the traversing rope including a foot control element for the throttle, and means moved by the hand of the operator while holding the bucket lever for controlling the brake and relief means.

21. The combination with a bucket of bucket ropes, winding drums and frictions, a pair of bucket operating levers, a traversing rope, a rope drum and a pressure fluid engine to turn the same, a brake for controlling the traversing rope, throttle and relief means, and a foot lever at the operator's position for moving the relief means.

22. In a hoisting apparatus, the combination with a bucket of a bucket operating lever, a traversing rope, a rope winding drum and pressure fluid engine to turn the same and controlling elements for the traversing rope at the bucket operator's position including a foot lever and a pivoted hand grip upon the bucket operating lever.

23. In a hoisting apparatus, the combination with a bucket of a pair of bucket operating ropes, rope winding drums, frictions and bucket operating levers, a traversing rope, a rope winding drum and pressure fluid engine to turn the drum, an engine control device, a brake for the drum, a pressure-fluid-actuated device to operate the brake, a valve for said pressure-fluid-actuated device, a pivoted hand grip and a bucket lever to control said valve, and a foot lever to operate said engine controlling device.

24. The combination with a hoisting bucket of a pair of bucket operating levers, a traversing rope, a rope winding drum, a pressure-fluid engine, the latter constantly connected to said drum, and means at the bucket operator's position for controlling the starting, stopping, and reverse movements of said drum and its connected engine.
25. The combination with a hoisting bucket of a pair of bucket operating levers, a traversing rope, a rope winding drum, a pressure fluid engine, the latter constantly connected to said drum, and means adapted to be controlled by the bucket operator while still maintaining his hold upon the bucket levers for controlling the starting, stopping and reverse movements of said drum and its connected engine.
26. The combination with a hoisting bucket of a pair of bucket operating levers, a traversing rope, a rope winding drum, a pressure fluid engine, the latter constantly connected to said drum, and means including a grasping device upon the bucket levers and adapted to be controlled by the bucket operator while still maintaining his hold upon the bucket levers for controlling the starting, stopping and reverse movements of said drum and its connected engine.
27. In a hoisting apparatus, the combination with a bucket of a pair of bucket levers, a traversing rope, a rope winding drum and a pressure-fluid engine connected to turn the drum, throttle means, engine relief means, means controlling said throttle means and said relief means at the bucket operator's position including a grasping device mounted on one of the bucket operating levers.
28. The combination with a bucket of a pair of bucket operating levers, a traversing rope, a rope winding drum, a pressure fluid engine to turn the drum, throttle means, relief means and a single control element for controlling both the throttle means and the relief means from the bucket operator's position.
29. The combination with a bucket of a pair of bucket levers, a traversed support, a traversing rope, a rope winding drum, a pressure fluid engine to turn the same, engine relief means, throttle means, a brake for said drum and two controlling elements at the bucket operator's position for controlling said relief means, throttle and brake, including a manually actuated member connected to one of the bucket levers.
30. The combination with a bucket of a pair of bucket levers, a traversed support, a traversing rope, a rope winding drum, a pressure fluid engine to turn the same, engine relief means, throttle means, a brake for said drum, and two controlling elements at the bucket operator's position for controlling said relief means, throttle and brake including a grasping device mounted upon one of the bucket levers.
31. The combination with a bucket of a pair of bucket levers, a traversed support, a traversing rope, a rope winding drum, a pressure fluid engine to turn the same, engine relief means, throttle means, a brake for said drum, and two controlling elements at the bucket operator's position for controlling said relief means, throttle and brake including a manually actuated control element adapted to be moved by the bucket operator.
32. The combination with a bucket of a pair of bucket levers, a traversed support, a traversing rope, a rope winding drum, a pressure fluid engine to turn the same, engine relief means, throttle means, a brake for said drum, and two controlling elements at the bucket operator's position for controlling said relief means, throttle and brake including a member adapted to be moved by the bucket operator while maintaining his hold upon the said bucket levers.

In testimony whereof, we have signed our names to this specification in the presence of two subscribing witnesses.
